United States Patent Office

Des. 194,281
Patented Dec. 25, 1962

194,281

SOCK

Paul E. Johnson, Jr., P.O. Box 324, Marietta, Ga.

Filed Mar. 6, 1961, Ser. No. 64,161

Term of patent 14 years

(Cl. D47—7)

The FIGURE is a side elevational view of a sock showing my new design. The design on the sock is continuous, the side opposite to that shown being substantially the same.

I claim:

The ornamental design for a sock, as shown and described.
